UNITED STATES PATENT OFFICE

2,078,401

CASING CUTTER

Neal Thomas McCann, Westminster, Calif.

Application August 20, 1934, Serial No. 740,615

10 Claims. (Cl. 81—195)

This invention relates to a casing cutter and is disclosed in this application as an inside casing cutter.

An object of my invention is to provide a novel pressure producing means within the tool itself, and operable on rotation of the tool, this pressure producing means forcing a fluid against a piston and thereby forcing the cutters outwardly to sever the pipe.

Another object is to provide a novel means of stopping the functioning of the pressure producing means when cutters have been extended and the pipe has been severed.

Still another object is to provide a means for returning the fluid from behind the piston after the cut has been made, so that the tool is returned to its original closed position and is ready for another cut.

An advantage of my invention is that the tool can be lowered to any point in the well and the pipe severed at that point, after which the tool can be raised or lowered to another position and another cut or cuts made.

Other objects, advantages and features of invention may appear from the accompanying drawing, the subjoined detailed description and the appended claims.

In the drawing:

Figure 1 is a longitudinal, sectional view of my casing cutter.

Figure 2 is a longitudinal, sectional view of the pump and the fluid conduit.

Figure 3 is a sectional view taken on line 3—3 of Figure 1.

Figure 4 is a sectional view taken on line 4—4 of Figure 2.

Figure 5 is a longitudinal, sectional view on an enlarged scale of the pump plunger and valve.

Figure 6 is a fragmentary, longitudinal, sectional view of my tool showing a modified type of cutter construction.

Referring more particularly to the drawing, the numeral 1 indicates a housing on the upper end of which is provided a box 2. The drill pipe 3 screws into the box and the tool is operated by rotation of the drill pipe as will be further described.

The box 2 extends into the top of the housing 1 and is held in position by a cap 4 which screws onto the upper end of the housing. The box 2 is splined into the housing 1 as shown at 5, but the box has a limited longitudinal movement relative to the housing, the purpose of which will be further described.

A power piston 6 is mounted in the bore 7 within the housing 1, suitable packing 8 being provided on the piston 6 for the purpose of preventing leakage around this piston. A plurality of cutters 9 are pivotally mounted on the piston 6, and these cutters are adapted to be projected outwardly through slots 10 in the wall of the housing 1.

A coil spring 11 bears against the bottom of the piston 6 for the purpose of yieldably urging this piston upwardly, and to return the piston to its starting position shown in Figure 1.

A conduit 12 is attached to the box 2 by means of a pin 13 which extends through the box and through the conduit. A port 14 in the conduit permits fluid under pressure to flow into the box 7 above the piston 6 for the purpose of forcing the piston downwardly and the cutters 9 outwardly as will be further described. A coil spring 12' presses against the top of the conduit 12 to press the conduit downwardly if wear occurs around the pin 13.

The conduit 12 extends axially through the piston 6 and projects below the piston. Suitable packing 15 surrounds the conduit adjacent the upper end thereof to prevent leakage. The lower end of the conduit seats upon a nut 16, the nut being screwed into the upper end of a cylinder block 17.

The cylinder block 17 is held stationary within the housing 1. An axial bore 18 in the block 17 is aligned with the hollow nut 16. A pump plunger 19 is reciprocally mounted in the bore 18 for the purpose of forcing fluid under pressure upwardly in the conduit 12, and thence above the piston 6 for the purpose of forcing this piston downwardly. The cylinder block 17 is held stationary in the housing by the spring 11 which presses against the base of the block and also by suitable pins or the like (not shown) which extend thru the base flange of the block and into the housing.

A valve 20 is seated above the plunger 19 for the purpose of holding the pressure produced within the conduit 12. The plunger 19 is slotted and fluid flows into the plunger through ports 21. The ports 21 communicate with ducts 22 in the block 17. The space around the block 17 within the housing 1 is filled with a liquid such as oil, and this liquid will therefore flow through the ducts 22 thence through the ports 21 and will be forced upwardly under pressure past the valve 20 as the plunger 19 reciprocates.

A cam sleeve 23 is journaled in the block 17

below the plunger 19. The cam sleeve is provided with a cam slot 24. A pin 25 extends transversely through the plunger 19 and projects into the cam slot 24. It will be evident 5 that when the sleeve 23 is held stationary by the clutch plate (to be subsequently described) and the plunger 19 and the housing 1 are rotated then the plunger will be reciprocated so as to build up pressure.

10 The plunger 19 is non-rotatably held in the block 17 by means of the lugs 26 on the block which projects into longitudinal slots 27 in the plunger.

A clutch plate 28 engages the sleeve 23 in that 15 there is a tongue and groove coupling on the plate and sleeve. A spring 29 bears against the clutch plate 28 for the purpose of yieldably holding the clutch plate in engagement with the sleeve 23. A shaft 30 is splined into the clutch 20 plate 28, and this shaft projects downwardly out of the bottom of the housing 1. A plurality of springs 31 are attached to the lower end of the shaft 30, and these springs press against the inner wall of the casing or pipe for the purpose of 25 holding the shaft 30 against rotation.

Thrust bearings 32 are provided on the shaft 30 for the purpose of reducing the friction between 30 the shaft and housing 1. The springs 31 bear against the casing with sufficient pressure to carry the entire load of the tool without slipping. Thus it will be evident that the shaft 30 will be held stationary while the housing 1 is rotated by the drill pipe 3.

The clutch plate 28 and the sleeve 23 will both 35 be held stationary relative to the housing 1 since the shaft 30 is attached to the plate and the shaft is held by the springs 31. Therefore the plunger 19 will be reciprocated as the pin 25 traverses the cam slot 24. As the plunger reciprocates, fluid under pressure is forced upwardly in the conduit 12 and the plunger 6 will be forced downwardly.

The cutters 9 will be moved outwardly into engagement with the casing, and the rotation of 45 the housing 1 and the cutters will sever the casing. The downward movement of the plunger 6 compresses the spring 11.

A pair of trip rods 33 extend vertically through the block 17. When the plunger 6 has been 50 lowered a distance sufficient to extend the cutters 9, the maximum amount, the plunger engages the trip rods and will force the plate 28 downwardly. The clutch connection between the plate 28 and the sleeve 23 is thus broken and the sleeve is then free to rotate with the housing. The plate 28 is slidably mounted on the shaft 30 and when the plate disengages the sleeve 23, said sleeve is no longer held stationary and therefore can rotate with the housing. This will stop 55 the action of the plunger, and no more fluid is forced back of the plunger 6.

If it is desired to withdraw the cutters 9 and remove the tool or change its position, the drill pipe is pulled upwardly. The box 2 is thus 65 moved upwardly relative to the housing 1 because of the lost motion connection between the two. The conduit 12 attached to the box 2 is thus moved off of its seat on the nut 16, and the fluid will drain back through the conduit into 70 the space around and above the block 17.

In Figure 6 I have illustrated a modified form 75 of cutter mounting. A plurality of cutters 34 are pivotally mounted in the housing 1 and in slots 35 in the housing. The plunger 36 is formed with cam surfaces 37 which engage the

inner face of the cutter 34 and swing these cutters outwardly around their pivots as the plunger is urged downwardly under pressure substantially as previously described.

In operation, my tool is lowered in the casing to the point desired. The springs 31 press tightly against the inner wall of the casing and hold the shaft 30 against rotation. The drill pipe to which the tool is attached is now rotated and the body of the tool rotates with the drill pipe. A 10 clutch plate 28 on the top of the shaft 30 engages the cam sleeve 23, thus holding this cam sleeve stationary relative to the rotative movement of the body of the tool. The pin 25 on the pump plunger 19 operates in the cam slot 24, 15 thus causing the plunger to reciprocate and forcing the fluid in the space around the cylinder block upwardly into the conduit 12. The fluid under pressure passes out of the port 14 above the piston 6. The pressure of the fluid forces 20 the piston downwardly and the cutters 9 outwardly. The cutters engage the casing and the rotation of the body of the tool causes the cutters to sever the casing. When the cut is completed, the drill pipe is lifted, and the lost motion connection between the blocks 2 and the housing permits the conduit 12 to be lifted off of its seat in the nut 16. The fluid above the piston then drains back thru the conduit into the space around the cylinder block and the spring 11 pushes the piston upwardly and retracts the cutters 9. When the piston 6 is pumped 30 downwardly, as previously described, and adjacent the lower end of its movement, the trip rods 33 will be engaged and pushed downwardly. These rods which engage the plate 28, will force 35 said plate downwardly thus disengaging the plate and the sleeve 23 which disengagement causes the pump to cease functioning because the drive to the sleeve 23 is broken, and therefore the pump 40 will cease to reciprocate.

Having described my invention, I claim:

1. A casing cutter comprising a housing adapted and arranged to be mounted on pipe, a piston 45 slidably mounted in the housing, a plurality of cutters in the housing, said cutters being engageable by the piston to project said cutters from the housing, a pump in the housing, means operably engaging the pump to operate the same upon rotation of the housing, and means engageable by the piston, said last named means engaging the pump operating means, whereby the pump operating means is released when the piston reaches the bottom of its stroke.

2. A casing cutter comprising a housing adapted and arranged to be mounted on drill pipe, a piston 50 slidably mounted in the housing, a plurality of cutters in the housing, said cutters being engageable by the piston to project said cutters from the housing, a pump in the housing, means operably engaging the pump to operate the same upon rotation of the housing, a conduit extending from the pump to the piston whereby pressure is exerted on the top of the piston, and means operable on upward movement of the housing to open said conduit whereby fluid is returned to the pump.

3. A casing cutter comprising a housing adapted to be attached to pipe, a plurality of cutters 70 in the housing, said cutters being adapted and arranged to be projected outwardly from the housing, a pump means, drive means for the pump, said drive means being operable as the housing is rotated, automatic means to release 75

said drive means, and a conduit extending from the pump to the piston whereby fluid under pressure is conducted to the piston.

4. In a fluid actuated casing cutter, fluid pressure producing means in the cutter, means operable on rotation of the casing cutter to actuate said pressure producing means, and automatic means connected to the pressure producing means whereby the pressure producing means is stopped 10 at the termination of the cutting stage of operation, a plurality of cutters, a piston, said cutters being attached to the piston, said fluid pressure producing means being adapted and arranged to exert pressure against the piston and to move 15 the same whereby the cutters are extended.

5. A casing cutter comprising a housing adapted to be attached to pipe, plurality of cutters in the housing, said cutters being adapted to be projected outwardly from the housing, a piston 20 in the housing, said piston engaging the cutters to extend them outwardly, a pump within the housing and rotatable therewith, a cam engageable by the pump whereby the pump is reciprocated, means to hold said cam stationary relative to the 25 pump, said pump being adapted and arranged to exert pressure against the piston.

6. A casing cutter comprising a housing adapted to be attached to pipe, a plurality of cutters in the housing, said cutters being adapted to be projected outwardly from the housing, a piston 30 in the housing, said piston engaging the cutters to extend them outwardly, a pump within the housing and rotatable therewith, a cam engageable by the pump whereby the pump is reciprocated, 35 means to hold said cam stationary relative to the pump, said pump being adapted and arranged to exert pressure against the piston, an automatic means to release said cam holding means.

40 7. A casing cutter comprising a housing adapted to be attached to pipe, a plurality of cutters in the housing, said cutters being adapted to be projected outwardly from the housing, a piston in the housing, said piston engaging the cutters 45 to extend them outwardly, a pump within the housing and rotatable therewith, a cam engageable by the pump whereby the pump is reciprocated, means to hold said cam stationary relative to the pump, said pump being adapted and ar- 50 ranged to exert pressure against the piston, and a conduit extending from the pump to the piston.

8. A casing cutter comprising a housing adapted to be attached to pipe, a plurality of cutters in the housing, said cutters being adapted to be projected outwardly from the housing, a piston in the housing, said piston engaging the cutters 5 to extend them outwardly, a pump within the housing and rotatable therewith, a cam engageable by the pump whereby the pump is reciprocated, means to hold said cam stationary relative to the pump, said pump being adapted and 10 arranged to exert pressure against the piston, an automatic means to release said cam holding means, and a conduit extending from the pump to the piston.

9. A casing cutter comprising a housing 15 adapted to be mounted on pipe, a plurality of cutters in the housing, a piston in the housing, said piston being adapted and arranged to extend the cutters from the housing, a pump within the housing and rotatable therewith, a cam 20 sleeve, means coupling the cam sleeve and the pump together whereby the pump is reciprocated upon relative rotation of the cam sleeve and pump, a clutch plate engaging the cam sleeve, a stationary shaft, means on the shaft whereby 25 said shaft is held stationary relative to the housing, said shaft being attached to said plate, a tripod engaging said plate, said tripod being engageable by the piston on downward movement 30 of the piston whereby the clutch plate is released from the cam sleeve.

10. A casing cutter comprising a housing 35 adapted to be mounted on pipe, a plurality of cutters in the housing, a piston in the housing, said piston being adapted and arranged to extend the cutters from the housing, a pump within the housing and rotatable therewith, a cam sleeve, means coupling the cam sleeve and the pump together whereby the pump is reciprocated upon relative rotation of the cam sleeve and 40 pump, a clutch plate engaging the cam sleeve, a stationary shaft, means on the shaft whereby said shaft is held stationary relative to the housing, said shaft being attached to said plate, a tripod 45 engaging said plate, said trip rod being engageable by the piston on downward movement of the piston whereby the clutch plate is released from the cam sleeve, and a conduit extending from the pump to the piston whereby fluid under 50 pressure is conducted to the piston.

NEAL THOMAS McCANN.
